(57) **CLAIM**

The ornamental design for a star-shaped snow guard, as shown and described.

DESCRIPTION

FIG. 1 is an elevational view of a star-shaped snow guard showing my new design, taken perpendicularly to the major axis of the base member;

FIG. 2 is a bottom plan view thereof;

FIG. 3 is a side elevational view thereof;

FIG. 4 is a top plan view thereof, taken along the axis of the body member;

FIG. 5 is an elevational view thereof, taken perpendicularly to the body member of the snow guard, corresponding to lines 5—5 of FIG. 3; and,

FIG. 6 is an elevational view thereof, taken perpendicularly to the body member of the snow guard, corresponding to lines 6—6 of FIG. 3.
